UNITED STATES PATENT OFFICE.

EBENEZER WHYTE, OF KANSAS CITY, MISSOURI.

PRICE-TICKET HOLDER.

SPECIFICATION forming part of Letters Patent No. 263,272, dated August 22, 1882.

Application filed June 2, 1882. (No model.)

To all whom it may concern:

Be it known that I, EBENEZER WHYTE, a citizen of the United States, residing at Kansas City, in the county of Jackson and State 5 of Missouri, have invented certain new and useful Improvements in Price-Ticket Holders, of which the following is a specification, reference being had therein to the accompanying drawings.

10 My invention relates to an improvement in price-ticket holders; and it consists in the shaft A, having the tang b, collar C, thimble A', and thimble-bar e, and in the combination and arrangement of the parts, as hereinafter more 15 specifically described.

Figure 1 is a front elevation of my improvement; and Fig. 2 is a side elevation thereof, showing the price-ticket.

A represents the shaft of the ticket-holder, 20 having the vertical slit a, Fig. 1, for reception of the ticket B. The shaft has rigidly secured in the lower end thereof the tang b, and is prevented from splitting by the tapering metallic collar C, which is rigidly fastened on its lower 25 end. The shaft is secured in a vertical position by tang b. It has also rigidly secured therein the horizontal thimble-bar e, which

catches the thimble A' when released from the upper and enlarged part of the shaft, and prevents its falling off the shaft. The shaft is 20 made tapering from top to bottom. Hence the thimble A', which fits loosely thereon, when resting on the thimble-bar e, compresses and 25 springs together the shaft at slit a when pressed upward on it, and thus causes the slotted end 35 of the shaft to clasp the price-ticket B when inserted in the slit, holding it securely in position.

Thus constructed, the price-ticket may be 40 readily removed from the slits and others inserted to suit samples or commodities, the price of which, being marked on the tickets, is thus advertised.

What I claim, and desire to secure by Letters Patent, is—

45 The combination of the shaft A, having slit a, thimble A', and tang b, substantially as shown, and for the purpose described.

In testimony whereof I affix my signature in presence of two witnesses.

EBENEZER WHYTE.
